Fig. 3

Fig. 4

Fig. 5

FIG. 1 is a side elevational view of the fishing lure of the present design, the opposite side is a mirror image of the side shown;

FIG. 2 is a top plan view of the fishing lure of FIG. 1;

FIG. 3 is a front elevational view thereof;

FIG. 4 is a rear elevational view thereof; and

FIG. 5 is a bottom plan view thereof.

The characteristic features of my design reside in the reversely curved undersurface and the inclined, planar truncated rear end in combination with the eyes bulging outwardly from flat, parallel sides and the flattened upper surface at the front end.

I claim:

The ornamental design for a fishing lure, as shown and described.
